(57) **CLAIM**

The ornamental design for a sandbag, as shown and described.

DESCRIPTION

FIG. 1 is a first perspective view of a sandbag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2; and,

FIG. 11 is an enlarged view of the selected portion 11 in FIG. 4.

The broken lines shown in the drawings depict portions of the sandbag that form no part of the claimed design.

The dash-dot-dash broken lines depict cut lines of the enlarged portions and form no part of the claimed design.

1 Claim, 11 Drawing Sheets
